UNITED STATES PATENT OFFICE.

ROBERT H. LAWSON, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

METHOD OF MAKING STOCKINGS.

Original application filed January 15, 1923, Serial No. 612,585. Divided and this application filed May 12, 1923. Serial No. 638,521.

To all whom it may concern:

Be it known that I, ROBERT H. LAWSON, a citizen of the United States, and a resident of Central Falls, in the county of Providence and State of Rhode Island, have invented an Improvement in Methods of Making Stockings, of which the following description, in connection with the accompanying drawings, is a specification, like characters on the drawings representing like parts.

This invention relates to the method of making stockings, particularly seamless-knit stockings.

15 This application is a division of my prior application, Serial No. 612,585, filed January 15th, 1923.

In order that the principle of the invention may be readily understood, I have in 20 the accompanying drawing disclosed one type of stocking, and will set forth the best mode known to me for producing the same in accordance with my invention.

In the drawing,—

25 Fig. 1 is a side elevation of a so-called seamless-knit stocking produced in accordance with my method;

Fig. 2 is an enlarged detail showing a portion of the suture seam, both at the inclined portion thereof and at the portion thereof that is parallel with the wales; and

30 Fig. 3 is a detail showing a portion of the back of the stocking made in accordance with my invention.

35 My invention while applicable to the production of numerous types of stockings, more particularly relates to the manufacture of stockings having a reinforced or contrasting area at the back of the leg and in the high splice.

40 I have not herein disclosed mechanism for producing the fabric of my invention. While the fabric may be produced upon many different types of machines, it is desirably produced upon a so-called Banner machine, fully disclosed in United States patent to Joshua B. Hemphill, No. 933,443, dated September 7, 1909.

45 The stocking produced in accordance with my invention is a so-called seamless structure, by which is meant—in the specific instance of a stocking—one devoid of selvage edges and knitted as a tubular structure, although the toe of the stocking is looped or

50 sewed as the final operation following the knitting. The said stocking is in accordance with my invention provided with certain suture seams which are, however, produced during the formation of the stocking and as a part of the knitting operation. I 55 will briefly refer to mechanism which may be employed and will then describe in detail the selected embodiment of stocking and the method by which it is made.

55 By means of the mechanism of the knitted machine of whatever circular type employed, the needle cylinder or the cam cylinder is or may be given at certain times in the knitting operation a continuous rotary movement, as, for example, during the knitting of the welt 60 portion 1 of the stocking, while at other times said cylinder is given a to or fro or reciprocating movement for the formation of the leg portion 2, or such portion thereof as is provided with the stripe hereinafter 65 referred to, as well as for the formation of the high splice portion 3 and the corresponding ankle portion 4, and also for the formation of the upper portion 5 and the sole portion 6 of the foot. The heel 7 and 70 the toe 8 are desirably knitted by a narrowing and widening portion in the customary manner.

75 Stockings have long been knitted with relatively narrow vertical stripes in the leg, 80 but so far as I am aware said stripes have either been made by introducing an additional yarn which at certain parts of the stocking is floated, or by substituting a yarn, or by a plating operation. In none of these 85 cases, however, has the stripe been defined at its lateral edges by suture seams constituting the lines of union between the stripe and the adjoining part of the stocking.

90 In accordance with my method, I provide the stocking with a vertical or lengthwise running relatively narrow stripe in the leg portion, such stripe being either of the full length of the leg portion below the welt as indicated at 9 in Fig. 1, or of some lesser 95 length, as, for example, extending from the dotted line 9' a short distance above the top of the high splice 3 to and merging into said high splice.

95 The stripe 9 may, after the completion of 100 the knitting of the stocking, be run through a sewing machine by which a sewed mock seam is provided centrally of the stripe 9,

but my invention is not limited to the production of such a structure. The stripe 9 is relatively narrow compared with the entire circumference of the stocking and the yarn 5 or thread producing the same and which is indicated at 10 in Fig. 2 may contrast in color, size or other characteristic with the thread or yarn 11 from which the rest of the leg 2 and the top 5 of the foot is or 10 may be knitted. For purposes of description, it will be assumed that the yarn 10 of the stripe 9 differs in weight from the yarn 11, so as to make a well defined contrasting stripe.

15 The high splice 3 is desirably of a tapering contour as indicated, and the sloping edges, one of which is indicated at 12 in Fig. 1, are also defined by suture seams. Therefore in effect the tapered high splice 20 3 is a continuation of the stripe 9, and there is thus presented in the stocking a stripe, parts of which are of different width. So far as I am aware, stripes as heretofore constructed have been of a uniform width, as 25 the so-called clocks of stockings are not stripes.

Through the formation of suture seams at opposite sides of the stocking, namely, at the opposite edges of the stripe 9 and opposite edges of the tapered high splice 3, there is presented a reinforced or contrasting area, parts of which have marginal lines 30 non-parallel to the wales of the fabric, that is, crossing a series of consecutive wales of 35 the fabric.

The stocking may be commenced at either 40 end, as, for example, at the top of the leg or the top of the toe, and therefore the suture lines of the tapered high splice either commence or terminate in proximity to each other, that is, at the points 13. I will more 45 particularly describe a stocking wherein the knitting is begun at the top of the leg, in which case the suture lines may be begun at the point 14 and at a corresponding point 50 at the opposite side of the stocking. The suture lines or seams are continued at parallel lines, being parallel to each other and also to the wales of the stocking down to the 55 points 13 and thereafter they are continued as inclined lines, one of which is indicated at 12 in Fig. 1, and both of which are indicated at 12, 12' respectively in Fig. 3. Said suture lines or seams 12, 12' diverge or converge in straight, curved or irregular lines and desirably at equal angles or symmetrically.

60 The needles employed in producing the fabric may be of the latch needle or spring beard needle type. They are arranged in a circular series and are of a number consistent with the diameter of the work to be performed upon the machine. For the knitting of the leg portion of the stocking, I desirably provide those needles which are to make

the stripe 9 with butts which differ in length from the butts of the needles knitting the front half of the leg of the stocking, the yarn or thread for the stripe 9 being introduced through a different yarn finger from

70 that through which the yarn is introduced for the remainder of the leg. Desirably such yarn fingers are at diametrically opposite sides of the needle cylinder. The entire circle of needles may be regarded as divided

75 into two substantially equal sets, one set having long butts and being known as instep needles which are adapted to be withdrawn from action during the formation of the heel and toe, but as hereinafter stated, the set

80 having the instep needles is supplemented by most of the needles from the other set, so that the stripe 9 is of the desired, relatively narrow, width. During the knitting of the

85 tapered high splice 3, I desirably automatically transfer certain needles from the larger of said sets to the smaller as the work progresses, so that the number of needles in the smaller group is increased from time to time, as, for example, at every course or at alternate courses, and the number of needles in

90 the larger group is correspondingly decreased. This result or action I desirably effect automatically and desirably for the manufacture of the stocking herein shown

95 I place the long butt or instep needles in one group and also in that same group I place a certain number of the short butt needles—desirably all of the heel-fashioning needles—leaving in the second group

100 only the remaining short butt needles which are merely sufficient in number to form the stripe 9 of whatever width desired. Desirably and as herein indicated the stripe

105 line is of a width substantially corresponding to that of a number of wales in the non-fashioning part of the stocking as clearly illustrated in Figure 1. This construction permits me to use for the stripe 9 only the non-fashioning needles of the heel or short butt

110 needles and in this case each inclined line 12 indicates the extent of the group of fashioning needles at each side of the stocking, it being observed that the inclined line 12 substantially corresponds in length with that of the line 14' indicating the narrowing and

115 widening seam for the heel. The stripe 9 is therefore markedly less in width than the full width of the high splice 3 and preferably comprises not to exceed substantially one-sixth of the circle of needles. The

120 numbers in the two groups obviously may differ somewhat in accordance with the different effects to be produced, and the direct control of such needles may be effected by jacks located below and in the grooves of the short butt needles. In the disclosed embodiment of the stocking, the width of the

125 stripe 9 may be such as to necessitate the employment of a comparatively small num-

ber of needles, and at the commencement of the high splice 3, that same number of needles is utilized, but as the knitting of the high splice continues the number of needles in the smaller group is constantly increased by additions at each end of the group from the larger group.

The periods when needles are transferred from one group to the other and the number 10 that are so transferred from time to time depend upon the configuration of the reinforced or contrasting area.

The stocking may be commenced either 15 at the top of the leg or at the toe, and I will describe as the preferred method of manufacture the knitting of the stocking beginning at the top of the leg, in which case circular knitting proceeds in the ordinary manner through the formation of the 20 welt 1, that is, down to the top of the stripe 9, which, as stated, may commence at any predetermined point. The leg portion or so much thereof as contains the stripe 9 and also that part thereof having the high 25 splice 3, is produced by reciprocating knitting, using two yarns which are introduced through two opposed thread guides or yarn fingers. The needles are divided into two substantially equal groups, the front half 30 of the stocking being knitted upon the long butt or instep needles and the back half of the stocking including the stripe 9 being knitted upon the short butt needles. By the use of jacks positioned under, and in the 35 grooves of, the short butt needles, all of the short butt needles excepting those needed for knitting the stripe 9, are automatically grouped with and function as long butt needles and hence all of the needles except 40 those for forming the stripe 9, take the so-called auxiliary yarn 11 which is preferably fed through the auxiliary yarn guide or finger. The needles which form the stripe 9 take only the yarn 10, which is the 45 so-called primary yarn and is fed through the other or regular yarn guide or finger. Thus for each reciprocation during the 50 knitting of the leg from the line 14^a down to the points 13 the needles act in two groups, one containing only the needles for the stripe 9 and the other containing all the other needles. The number of needles in the two such groups remains unchanged until the points 13 are reached, and then 55 the number of needles in the rear group is constantly augmented from the needles of the front group, thereby forming the tapering enlargement or high splice 3, which is thus a continuation of and a widening of 60 the stripe 9. This transfer of needles from the front group to the rear group continues in accordance with the shape that is to be given the high splice 3 until the line 14, 14 is reached at the top of the heel 7. There- 65 upon one half the needles, namely, the long

butt or instep needles are thrown out of action while retaining their loops and the heel 7 is formed by a narrowing and a widening operation in the usual manner. Then the instep needles are restored to action and the foot is knitted preferably by reciprocating knitting, thereby providing along each side of the foot a suture seam 15. Thereafter the toe 8 is knitted by a narrowing and widening action in the usual way, 75 and the stocking is then seamed up at the toe along the line 16.

The yarn 11 may be used in forming the upper part 5 of the foot, or a different 80 yarn may be substituted therefor. The sole of the foot may be knitted from the same yarn used to knit the stripe 9 or a different yarn may be substituted. Desirably the yarn used for knitting the high 85 splice 3 is the same yarn as that used for knitting the stripe 9, but a different yarn may be employed and in any event the yarn or yarns used in knitting the heel and toe are different from the yarns used for knitting the stripe 9.

The stripe 9 and the high splice 3 are desirably composed of the yarn 10 introduced at the regular side of the machine, namely, the side where the series of yarn fingers are located, and the remainder of each course is desirably knitted upon the so-called auxiliary side. During the formation of the high splice 3 more and more needles knit on the regular side, that is, at the heel side 90 of the stocking. I have stated that the foot is preferably made by reciprocating knitting resulting in the formation of suture seams, one of which is indicated at 15. In so forming the foot a transfer of needles 100 may be effected from one group to the other according to the desired contour of the upper and sole portions of the foot, but it will be assumed for clearness of description that in making the foot, there is no transfer of needles from one group to the other, and that therefore the suture seams 15 of the 105 foot portion are straight and parallel and in the direction of the wales, being at opposite sides of the foot and there defining the upper part of the foot and the sole.

In knitting the stripe 9, what may be termed the suture needles continue to be the same identical needles, and there is but a single suture needle at each edge of the stripe 9, but in knitting the tapered high 110 splice 3, what may be termed the suture needles are constantly changing, and there are two suture needles at each edge of said 115 tapered high splice; that is, one of the two needles at each edge of said tapered high 120 splice, and which is a suture needle in one stroke of reciprocation, is immediately thereafter depressed so as to join the needles at the back of the ankle or high splice part 125 of the stocking, and thereupon the next 130

needle becomes the other suture needle at that side, namely, the needle in the instep needles which is next to the suture needle that has just been transferred to the high 5 splice needles. This same action occurs at the same side or portions of the stocking during the knitting of the high splice, assuming the latter to be of a tapering form.

Within the scope of the invention I may 10 begin the knitting of the stocking at the toe instead of at the top of the leg. In such case the toe and the heel may be knitted in the usual way and the foot may be knitted by circular work or as a split foot, 15 and immediately upon the completion of the heel a short butt needle may be thrown up, this operation being repeated on each side until all the short butt needles excepting those needles for knitting the stripe 9, 20 are knitting at the auxiliary cam. The leg portion wherein the stripe 9 is to appear is then knitted in the manner already described.

In Fig. 2, I have diagrammatically indicated 25 a portion of the fabric formed in accordance with my invention. In each of the courses of the illustrated part of the fabric in this figure the secondary yarn 11 is used to form a loop at both sides of the heavier 30 or contrasting yarn 10, which is the primary yarn, namely, the yarn at the heel side of the ankle. The suture formation along the lines joining the primary yarn and the secondary yarn consists in alternate courses 35 of a loop and a partial loop of the primary yarn at one edge of the stripe 9 as indicated at 17, the intervening courses being similarly formed at the opposite edge of the stripe 9 as indicated at 18 in Fig. 2. Throughout 40 the formation of the stripe 9 the said loops and partial loops 17 and 18, respectively, are in alignment and in parallelism with the wales, but throughout the formation of the tapered high splice 3, said loops and 45 partial loops 17 are in an inclined line which crosses the wales, and the same is true of the loops and partial loops 18 at the opposite edge of the stripe 9 and of the tapered high splice 3. Thus at 50 one end of each partial course constituting the stripe 9 and the high splice 3, the primary yarn 10 is returned upon itself as indicated and is then introduced into the next succeeding course and at the end of 55 said succeeding course, said primary yarn 10 is again returned upon itself and then introduced into the next succeeding course, this operation being continued throughout 60 the formation of the stripe 9 and the high splice 3, the points in said courses at which the yarn is so returned upon itself being determined by the predetermined width of the stripe 9 and the tapering or other contour of the high splice 3. It will be observed 65 that at the end of each partial course

of the secondary yarn in the tapered high splice 3, as indicated at 19, primary yarn 10 is carried across two loops as indicated at 20 in Fig. 2, and is then introduced into the next succeeding course at 21 two wales removed from its terminal loop 19 in the preceding course. This operation is continued throughout the formation of the tapered high splice 3.

Having thus described the best mode 75 known to me for practicing the method of my invention, I desire it to be understood that although specific terms are employed, they are used in a generic and descriptive sense and not for purposes of limitation, the 80 scope of the invention being set forth in the following claims.

Claims—

1. That method of knitting upon a circular series of needles a tubular stocking having a markedly narrow, split work stripe along the median back line of the leg comprising introducing one yarn to a group of the non-fashioning heel needles only, introducing another yarn to all the remaining needles of the said circle of needles and including the instep needles and the fashioning heel needles of the second group, simultaneously knitting with said yarns respectively upon both groups of said needles by reciprocating knitting, and in so doing interconnecting said two yarns by suture seams, thereby forming split work; and during the forming of the lower part of said stripe persistently transferring the fashioning heel needles from the larger to the smaller group, and in so doing causing at least one of said suture seams to cross wales of the fabric.

2. That method of knitting upon a circular series of needles a tubular stocking having a markedly narrow, split work stripe along the median back line of the leg comprising introducing one yarn to a group of non-fashioning heel needles only, introducing another yarn to all the remaining needles of the said circle of needles and including the instep needles and the fashioning heel needles of the second group, simultaneously knitting with said yarns respectively upon both groups of said needles by reciprocating knitting, and in so doing interconnecting said two yarns by suture seams, thereby forming split work, and during the forming of the lower part of said stripe persistently transferring fashioning needles from both ends of the larger group to the smaller group, and in so doing causing both of said suture seams to cross wales of the fabric.

3. That method of knitting upon a circular series of needles a tubular stocking having a markedly narrow, split work stripe along the median back line of the leg comprising introducing one yarn to a group

of non-fashioning heel needles only, introducing another yarn to all the remaining needles of the said circle of needles and including the instep needles and the fashioning heel needles of the second group, simultaneously knitting with said yarns respectively upon both groups of said needles by reciprocating knitting, and in so doing interconnecting said two yarns by suture 5 seams, thereby forming split work, and during the forming of the lower part of said stripe and in a series of courses transferring all of the fashioning heel needles from the larger to the smaller group and in so doing 10 causing both of said suture seams to cross wales of the fabric to substantially narrow the heel pocket. 15

ing a markedly narrow, split work stripe along the median back line only of the leg, comprising introducing one yarn to a group consisting only of a part at least of the non-fashioning heel needles only, introducing another yarn to all the remaining needles of the said circle of needles and including the instep needles and a majority of the fashioning heel needles at both sides of the non-fashioning heel needles as a second group, simultaneously knitting with said yarns respectively upon both groups of said needles by reciprocating knitting and in so doing interconnecting said two yarns by suture 70 seams, thereby forming split work, 75 and during the forming of the lower part of said stripe persistently and throughout a series of courses transferring the terminal 80

4. That method of knitting upon a circular series of needles a tubular stocking having a markedly narrow, split work stripe along the median back line of the leg comprising introducing one yarn to a group of the non-fashioning heel needles only, introducing another yarn to all the remaining needles of the said circle of needles and including the instep needles and the fashioning heel needles of the second group, simultaneously knitting with said yarns respectively upon both groups of said needles by reciprocating knitting, and in so doing interconnecting said two yarns by suture seams, thereby forming split work, and during the forming of the lower part of said stripe persistently transferring terminal fashioning heel needles from the larger to the smaller group, there to act as suture needles and thus to cause both suture seams to extend obliquely to the wales of the fabric.

5. That method of knitting upon a circular series of needles a tubular stocking having a markedly narrow, split work stripe along the median back line only of the leg, comprising introducing one yarn to a group of the non-fashioning needles only, introducing another yarn to all the remaining needles of the said circle of needles and including the instep needles and the fashioning heel needles as a second group, simultaneously knitting with said yarns respectively upon both groups of said needles by reciprocating knitting, and in so doing interconnecting said two yarns by suture seams, thereby forming split work, continuing the split work to the heel, and thereby making said narrow stripe, and continuing the same as a high splice to the heel and

5. That method of knitting upon a circular series of needles a tubular stocking having a markedly narrow, split work stripe along the median back line only of the leg, comprising introducing one yarn to a group of needles composed exclusively of non-fashioning heel needles only, introducing another yarn to all the remaining needles of the said circle of needles and including the instep needles and the fashioning heel needles as a second group, simultaneously knitting with said yarns respectively, upon both groups of said needles by reciprocating knitting and in so doing interconnecting said two yarns by suture seams, thereby forming split work, and during the forming of the lower part of said stripe persistently and throughout a series of courses transferring the terminal fashioning heel needles from the larger to the smaller group, there to act as suture needles and thus cause both suture seams to extend obliquely to the wales of the fabric.

45 50 55 60 65 70 75 80 85 90 95 100 105 110 115 120 125

thereafter forming the heel, foot and toe of the stocking.

8. That method of knitting upon a circular series of needles a tubular stocking having a markedly narrow, split work stripe comprising introducing one yarn to a small group of the back or heel needles consisting of not exceeding one-sixth of said complete circle of the needles; introducing another yarn to all the remaining needles of said circle of needles and including the instep needles and substantially all the fashioning needles as a second group; simultaneously knitting with said yarns respectively, upon both groups of said needles by reciprocating knitting and in so doing interconnecting said two yarns by suture seams, thereby forming split work.

9. That method of knitting upon a circular series of needles a tubular stocking having a markedly narrow, split work stripe, comprising introducing one yarn to a group of the back or heel needles consisting of not

125

6. That method of knitting upon a circular-series of needles a tubular stocking having one-sixth of the entire circle of said needles; introducing another yarn to all 130

- the remaining needles of said circle of needles and including the instep needles and substantially all the fashioning needles as a second group; simultaneously knitting with 5 said yarns respectively, upon both groups of said needles by reciprocating knitting and in so doing interconnecting said two yarns by suture seams, thereby forming split work; and during the forming of the lower 10 part of said stripe persistently increasing the number of needles of the smaller group and correspondingly decreasing the number of needles of the larger group by regroupment of the circle of needles, but continuing 15 the interconnection of the yarns by suture seams, thereby forming a high splice, the lateral edges whereof are defined and bounded by suture seams.
10. That method of knitting upon a circular series of needles a tubular stocking having a markedly narrow, split work stripe, comprising introducing one yarn to a group of the back or heel needles of said circular series of needles, said group not exceeding 20 approximately the number of needles forming the wales in the non-fashioning part of the heel; introducing another yarn to all the remaining needles of the said circle of needles and including the instep needles and substantially all the fashioning needles; and simultaneously knitting with said yarns respectively, upon both groups of said needles by reciprocating knitting and in so doing interconnecting said yarns by suture 25 seams, thereby forming split work.
11. That method of knitting upon a circular series of needles a tubular stocking having a relatively narrow, parallel-sided, split work stripe at the rear of the leg above 30 the high splice, which comprises introducing one yarn only to a group of needles which are to form said stripe, said group being composed substantially wholly of non-fashioning heel needles; introducing another 35 yarn only to the remaining needles of the circle of needles; simultaneously knitting with said yarns respectively, upon both sets of said needles by reciprocating knitting to form both of said parts of the leg 40 of the stocking and in said reciprocating knitting interconnecting said two yarns by suture seams, each of which seams is restricted to a single wale only of the fabric throughout said parallel-sided stripe.
12. That method of knitting upon a circular series of needles a tubular stocking having a relatively narrow, parallel-sided, split-work stripe at the rear of the leg above 45 the high splice, which comprises introducing one yarn only to a group of needles which are to form said stripe, said group being composed substantially wholly of non-fashioning heel needles; introducing another 50 yarn only to the remaining needles of the circle of needles and including the instep needles and substantially all the fashioning needles; and simultaneously knitting with said yarns respectively, upon both groups of said needles by reciprocating knitting and in so doing interconnecting said yarns by suture 55 seams, thereby forming split work.
13. That method of knitting upon a circular series of needles a tubular stocking having a relatively narrow, parallel-sided, split-work stripe at the rear of the leg above 60 the high splice, the edges of which stripe substantially coincide with the junction of the non-fashioning and fashioning needles, which comprises introducing one yarn to a group of needles consisting of substantially all the non-fashioning heel needles, introducing another yarn to the remaining needles of the circle of needles; simultaneously knitting with said yarns respectively, upon both sets of said needles by reciprocating knitting to form the tubular part of the leg; and in said reciprocating knitting interconnecting said two yarns by suture 65 seams, each of which seams is restricted to a single wale only of the fabric throughout said parallel-sided stripe.
14. That method of knitting upon a circular series of needles a tubular stocking having a markedly narrow, split work stripe extending less than the length of the leg, comprising knitting by rotary knitting the upper part at least of the leg of the stocking; then as a continuation of such fabric, in the same machine, introducing one yarn to a group of the back or heel needles of said circular series of needles, said group not exceeding approximately the number of needles forming the wales in the non-fashioning part of the heel; introducing another 70 yarn to all the remaining needles of the said circle of needles and including the instep needles and substantially all the fashioning needles; and simultaneously knitting with said yarns respectively, upon both groups of said needles by reciprocating knitting to form the tubular part of the leg; and in said reciprocating knitting interconnecting said two yarns by suture 75 seams, each of which seams is restricted to a single wale only of the fabric throughout said parallel-sided stripe.
15. That method of knitting upon a circular series of needles a tubular stocking having a relatively narrow, parallel-sided, split-work stripe at the rear of the leg above 80 the high splice, which comprises introducing one yarn only to a group of needles which are to form said stripe, said group being composed substantially wholly of non-fashioning heel needles; introducing another 85 yarn only to the remaining needles of the circle of needles and including the instep needles and substantially all the fashioning needles; and simultaneously knitting with said yarns respectively, upon both groups of said needles by reciprocating knitting to form the tubular part of the leg; and in said reciprocating knitting interconnecting said two yarns by suture 90 seams, each of which seams is restricted to a single wale only of the fabric throughout said parallel-sided stripe.
16. That method of knitting upon a circular series of needles a tubular stocking having a relatively narrow, parallel-sided, split-work stripe at the rear of the leg above 95 the high splice, which comprises introducing one yarn only to a group of needles which are to form said stripe, said group being composed substantially wholly of non-fashioning heel needles; introducing another 100 yarn only to the remaining needles of the circle of needles and including the instep needles and substantially all the fashioning needles; and simultaneously knitting with said yarns respectively, upon both groups of said needles by reciprocating knitting to form the tubular part of the leg; and in said reciprocating knitting interconnecting said two yarns by suture 105 seams, each of which seams is restricted to a single wale only of the fabric throughout said parallel-sided stripe.
17. In testimony whereof, I have signed my name to this specification.

ROBERT H. LAWSON,
